STARLEY F. BEASLEY, OF KANSAS CITY, MISSOURI, ASSIGNOR OF ONE-HALF TO
FRANK E. WELLMAN, OF KANSAS CITY, KANSAS.

COLUMN-POST BEARING FOR BRAKE HANGERS.

Application filed February 7, 1927. Serial No. 166,493.

This invention relates to column post bearings for brake hangers, and has for its object to provide an additional bearing for the oscillating link supports of the brake beams customarily employed on railway cars and the like. With the actual type of construction employed on railway cars the supporting bearings formed on a part of the column post of railway trucks and the pins carried by said bearings, rapidly wear and eventually would lead to the dropping of the brake beams and probably result in the derailment of the car. The prime object of this invention, therefore, is to produce an auxiliary bearing which may be readily attached to railway trucks having brake beam supports of the type described, without necessitating replacement of any of the standard parts of the trucks, the auxiliary bearing not only prolonging the life of the standard bearings if employed before the latter are unduly worn, but greatly increasing their strength. When the standard bearing brackets are so worn as to endanger support of the beams, as outlined, it has heretofore been necessary to replace the entire post carrying the bearing brackets. The necessity of replacing such worn post is avoided by the use of my auxiliary bearings, as they are capable of carrying the beams and furthermore transfer the wear on the pins to an intermediate point which was not originally subjected to wear.

With the object named in view, the invention consists in certain novel and useful features of construction and arrangement of parts as hereinafter described and claimed; and in order that it may be fully understood reference is to be had to the accompanying drawing, in which:

Figure 1 is a section taken longitudinally through one side of a truck on the line I—I of Figure 2, to illustrate the post column support and one end of a brake beam pivotally suspended therefrom.

Figure 2 is a section on the line II—II of Figure 1.

Figure 3 is an enlarged section taken through the auxiliary bearing forming a part of the invention, as it will appear in operative position on the post column and with the pivot pin in position.

Figure 4 is a perspective view of the auxiliary bearing of the invention.

In the said drawing, where like reference

characters identify corresponding parts in all of the figures, 1 illustrates a post column interpositioned between upper and lower arch members 2 of a truck, and said post at its upper end is formed with a laterally extending arm, comprising flange portions 3 connected together by a reinforcing and stiffening web 4 at one of their edges, said web being formed with a central opening 4^a to lighten without impairing the strength 65 of the structure.

Integrally formed with the flanges 3 and 4, is a pair of similar spaced ears 5, formed with hublike extensions 5^a, said ears and extensions being formed with aligned openings for the reception of the supporting pivot pin 6. Encircling the opposite ends of the pin 6, are the opposite arms of a U-shaped supporting link 7 which pivotally carries the brake beam assembly 8 at its 75 lower end.

All of the construction above described is common and well known in the art and it is not believed that further description or recapitulation is necessary, other than to point out that the beam and pivot pin 6 and bearings 5 will, due to their intermittent action one upon the other, effect the elongation of the bearing openings and if neglected long enough, as occasionally happens, lead to the breaking thereof as pointed out in the introductory paragraph of this specification.

In order to provide an auxiliary bearing to increase the area of the bearing surfaces 90 or to serve as a substitute for the original points of pin support, I have produced an auxiliary bearing comprising a downwardly-opening hook-shaped upper portion 9 which overlies the upper flange 3 of the 95 supporting arm of the post 1 and engages the rear side of said arm, as illustrated in Figure 3. The auxiliary bearing is of width to snugly fit between the extensions 5^a, as shown in Figure 1, and is formed with a 100 tail or abutment 10 having a flat extremity which rests against the web 4 of the supporting post arm. The bearing has an opening 11 in alignment with the openings of ears 5, or with the upper ends of such ear 105 openings in the event they have become elongated downwardly through wear, as hereinbefore suggested, it being noted that the bearing suspended from the top of the post arm, retains the pivot pin 6 at its initial 110

and proper height, and that the wear on the pin is defined by the width of the bearing, the ears whether deformed by wear or not, guarding against dislocation of the auxiliary bearing under shock or jar incident to the travel of the car.

With the construction described it will be apparent that the device of the invention practically doubles or renews the bearing surface supplied the pin 6, without unduly increasing the weight of the brake mechanism, and that it may be easily and quickly placed in position to relieve badly worn post arms by the mere pulling of the pin 6, the insertion of the auxiliary bearing and the replacement of the pin. It is to be understood of course that the auxiliary bearing brackets may vary in proportion to suit the dimensions of the column post arm and the common type of ears forming the conventional bearing.

From the above description, it will be apparent that I have produced a device embodying the features of advantage set forth as desirable in the statement of the object of the invention, and which may be modified in various particulars without departing from the spirit and scope of the appended claims.

30. What I claim is:

1. The combination with a supporting arm having a pair of spaced ears provided with alined openings, a bearing pin engaging said openings, a brake hanger carried

by said pin, and an auxiliary bearing interposed between said ears and receiving said pin and suspended from and bearing against a vertical portion of the supporting arm.

2. The combination with a supporting arm having a pair of spaced ears provided with alined openings, a bearing pin engaging said ears, a brake hanger carried by said pin, an auxiliary bearing interposed between said ears and receiving said pin and having a hook terminal engaging the supporting arm above the plane of said pin and a tail member engaging a vertical portion of said arm below the plane of said pin.

3. A bearing, having a pivot-opening, a downwardly-opening hook above and facing transversely of said opening, and a tail in a plane below said opening and underlying said hook.

4. The combination with a supporting arm having an ear provided with an opening, a brake pin engaging said opening, a brake hanger carried by said pin, an auxiliary bearing receiving said pin and having suspension means above the pin in engagement with the arm and a tail below the pin bearing against an upright portion of said arm.

In witness whereof I hereunto affix my signature.

STARLEY F. BEASLEY.
